RADIO CRYSTAL DETECTOR

Filed March 22, 1923

Figure 3

Inventor;

Edward Alexander McMurtry

UNITED STATES PATENT OFFICE.

EDWARD ALEXANDER McMURTRY, OF CHICAGO, ILLINOIS.

RADIO CRYSTAL DETECTOR.

Application filed March 22, 1923. Serial No. 626,815.

My invention relates to crystal detectors for use in radio receiving sets and the objects of my invention are first, to provide new and improved constructions for said detectors whereby a crystal detector may be mounted on the back of the panel of a radio set and adjusted for sensitivity by the simple rotation of a knob and dial or other manually operated means on the front or control side of the panel; and second, to provide improved contact members for said detectors, which do not require visual adjustments or direct manual application, or poking around, upon the crystal surface; and which cannot become disengaged from or thrown out of contact with the crystal, or caught in the irregularities of the crystal or mounting thereof, or otherwise cease to function properly as the detector is adjusted by the turning of the knob and dial on the front of the panel.

I attain these objects by the mechanism illustrated in the accompanying drawing in which Figure 1 is a side view of my invention, Figure 2 is a perspective view of the same from the back of the panel, Figure 3 is a detailed representation of improved contact members, Figure 4 shows a rotating contact construction.

Similar numerals refer to similar parts throughout the several views.

Panel "19" represents a part of the panel of a radio set and is generally of hard rubber or other insulating material. Cup "5" with set screw "6" is used as a retainer for the crystal "7" which may be of silicon, galena or any other substance known and used at present in crystal detectors, for its rectifying properties. Attached to cup "5" is shaft "2" which extends through a hole in panel "19" as shown, and a knob and dial "1" is secured to shaft "2" by means of set screw "3". The knob and dial is on the control or front side of the panel. Washer "4" acts as a spacer between dial "1" and panel "19". Metal strip "8" of light spring brass or copper has two holes drilled therein, one to pass shaft and the other to pass screw "9". Screw "9" and nut "10" tightened down upon terminal connector "11" form one terminal of the detector.

Spring contact member "12" shown in detail in Figure 3 "a" is made of light flexible spring copper ribbon about three thousandths of an inch in thickness and about $\frac{1}{2}$ inch wide. Ribbon of brass or hard aluminum or similar metal will serve equally

well. It is punched as shown, hole "21" and eyelet "20" being of such size that screw "15" will pass through them freely. Eyelet "20" permits the smooth operation of spring "12" up and down screw "15" as thumb nut "18" is turned. A plurality of contact projections are embossed in the free end of spring "12", as shown at "13", and these contacts serve to engage the surface of the crystal "7". Terminal connector "14" is securely bolted to the back of panel "19" by nut "16" on screw "15". Screws "9" and "15" have their heads countersunk below the front surface of panel "19" and are obscured from view by the dial "1". Spring contact 12 is securely held between nuts "16" and "17" through hole "21". Eyelet "20" is slipped over the top of screw "15" and thumb nut "18" is screwed down until some of the contact projections "13" engage the crystal, and then about one half turn more is given the thumb nut "18" to obtain the correct contact pressure on the crystal.

The contact member may be adjusted or moved laterally and set to any desired position, over the crystal, or to one side thereof to permit removal of the crystal from its cup, by first loosening the nut 17 to permit the desired adjustment and then again tightening it to hold the contact member in the position to which it has been set. If desired the thumb nut 18 may be omitted, in which event the nut 17 becomes, in addition to being the means for permitting and securing lateral adjustment of the contact, also a means for regulating the tension of the contact as follows: By means of the nut 17 the contact member 12 is clamped at one side of, but close to, the cup containing the crystal 7, and then the spring member 12 carrying the contact is carefully bent so that the contact point or points are a short distance, say about a sixteenth of an inch, below the level of the crystal surface. Then upon adjusting the contact member over the crystal and securing it by the clamping nut 17 the contact point will be found to bear upon the crystal surface with the desired light pressure. This is an extremely accurate as well as simple method of regulating the pressure of the contact point 13.

The crystal is mounted so as to project slightly above the rim of the cup "5". If the crystal is mounted in soft metal it must project somewhat above the surface of the metal 110

so that contacts "13" do not touch any metal and thereby short circuit the device rendering it temporarily inoperative. The contact shown in Figure 3 "c" is serviceable, having 5 a pad of metal wool or finely matted conducting material soldered or otherwise secured to the spring "12" in place of the contacts "13", to engage the crystal surface. In Figure 3 "d" is shown a crystal retaining cup 10 soldered to the back of the spring strip "12" and a hole through the said strip corresponding with the hole in the cup permits the crystal to be mounted in the cup "24" and secured by the set screw "26." With a cup so 15 attached, the spring strip "12" is of somewhat heavier material than for the other kinds of contacts because of the weight of the cup and crystal which must be supported. In Figure 3 "b" is shown a single point contact embossed in the form of a flattened cone or pyramid which may be used with a crystal mounted even with or below the surface of the metal mounting and, like all of the contact forms described above, will operate 20 smoothly and without mechanical or electrical fault with the smoothest or most irregular of crystals or mountings and is a notable advance in contact construction for crystal detectors.

30 When a crystal of bornite is mounted in cup "24" and used in conjunction with a crystal of copper pyrites mounted in cup "5", the combination is what is universally known as a perikon detector.

35 Figure 4 shows a contact member made of metal ribbon "12" the same as for the contacts shown in Figure 3 "a", "b" and "c". It is bent as shown and secured to a shaft "2" by means of nuts "28" and "29" and takes the 40 place of the cup "5" of Figure 1. This may be used in conjunction with contact member "d" Figure 3. The plurality of contact points "13" are shown, but this may be like "b" or "c" Figure 3 for the contact surface. 45 This is an arrangement involving a rotary or moving contact with a stationary crystal mounting. It is obvious that the panel 19 indicated in the accompanying drawings, may be either the panel of the radio set proper, 50 or a small individual panel forming part of the detector element of the radio set. In the latter event the knob and dial 1 would be adjusted outward upon the shaft 2 sufficiently far to permit the usual panel to lie between the dial and the panel 19, and suitable means, 55 such as the bolts 9 and 15, would be employed to unite the two panels.

60 The detector is adjusted for sensitivity by slowly rotating the knob and dial 1 on the front or control side of the panel. Referring to Figure 1, this causes cup "5" and crystal "7" to rotate and contact points "13" explore the surface of the crystal as it moves under them.

65 Any crystal detector circuit may be em-

ployed and in this respect it is no different from any crystal detector now in use. It may be used wherever crystal detectors find a use, in conjunction with audion sets, in wave-meters, et cetera.

70 The universal practice up to the present time of mounting a crystal detector on the front of the panel has barred it as a part of any fine audion set, and made it none the less desirable on a crystal set, for its mechanism has been not only crude and unsightly, but for its adjustment it required a tedious poking around directly on the crystal surface with various kinds of coil springs or cat-whisker wires that have kept the crystal detector in the class of unreliable toys.

75 In the particular embodiment of my invention illustrated in the drawings the flat spring 12 serves as a means for limiting the lateral movements of the contact point or points 80 as the crystal is being moved or rotated beneath such contact or contacts. But other suitable means may be employed for limiting the lateral movements of the contact point and still come within the scope of my invention, and possess some of the advantages 85 thereof.

80 My invention overcomes all of these defects, and with its ease of adjustment, and simple knob and dial control, and back panel 95 mounting it is worthy of a place on the finest set.

90 I claim broadly the following constructions and combinations,—

1. In combination with a panel, of a crystal 100 detector comprising a crystal, a mounting therefor, an electric terminal connected with the crystal, a resilient spring carrying a contact adapted to engage with the surface of the crystal, means for adjusting the spring 105 to regulate the pressure between the contact and the crystal, means for restricting the lateral movements of the contact upon the crystal, the parts of the detector enumerated being located at the back of the panel, a 110 knob located at the front of the panel for adjusting the relative position of engagement of the contact with the crystal, and means for establishing electrical connection with the said contact spring. 115

2. In combination with a panel, of a crystal 120 detector comprising a crystal, a mounting therefor, an electric terminal connected with the mounting, a resilient spring carrying a contact adapted to engage the surface of the 125 crystal, means for adjusting the spring to regulate the tension of the contact, means for permitting the adjustment of said contact laterally, the parts of the detector enumerated being located at the back of the panel, a knob located at the front of the panel for rotating said crystal mounting, and means for establishing electrical connection with said resilient spring.

EDWARD ALEXANDER McMURTRY.
